Inventor

UNITED STATES PATENT OFFICE.

LAURITZ W. ANDERSEN, OF WATERBURY, CONNECTICUT, ASSIGNOR TO THE PLUME & ATWOOD MANUFACTURING COMPANY, OF WATERBURY, CONNECTICUT, A CORPORATION OF CONNECTICUT.

ELECTRIC HOLDER.

1,103,122.

Specification of Letters Patent.

Patented July 14, 1914.

Application filed February 17, 1914. Serial No. 819,225.

To all whom it may concern:

Be it known that I, LAURITZ W. ANDERSEN, a citizen of the United States, residing at Waterbury, in the county of New Haven and State of Connecticut, have invented a new and useful Improvement in Electric Holders, of which the following is a specification.

This invention relates generally to electric holders for indirect lighting and more particularly to a holder provided with a novel construction of socket shell holder, the object being to provide a device by means of which the holder can be attached to a socket 15 already wired to a fixture, thus saving both time and labor.

With this object in view my invention consists essentially in providing a separable socket shell holder together with means for 20 securing the sections together, said sections having the shade holding means attached thereto.

The invention consists also in certain details of construction hereinafter described 25 and pointed out in the claims.

In the drawings forming a part of this specification Figure 1 is a sectional elevation illustrating the particular application of my invention. Fig. 2 is a view of the separable 30 socket shell holder separated, and Fig. 3 is a detail view showing the same arranged about the socket and shell.

In this class of devices heretofore employed it has been impossible to attach the 35 holder without wiring in the socket on the fixture afterward, but this was very inconvenient and consumed considerable time and labor and with the idea of overcoming this defect I produce a separable socket shell holder A divided longitudinally as shown, 40 said sections being so shaped and sized that when brought together they provide a complete cover for the socket shell. At the upper end ample provision is made for the 45 socket bushing and at the lower ends the sections are provided with mating or continuous threads to receive a threaded ring B after the socket and shell has been inserted in the holder for the purpose of binding the 50 holder upon the socket and shell. Arms C extend from the sections of the separable holder and at their lower ends are connected to an inner disk D, which disk D is provided with a centrally extending threaded

post E. This inner disk fits into the central 55 opening of the shade or glassware and the outer cup F fits upon the under side thereof and a nut G screwed upon the extending end of the threaded post securely binds the shade or glassware between the inner disk and 60 outer cup.

In Fig. 1 of the drawing I have shown the socket of the keyless type, but in Fig. 3 I have shown the socket provided with a pull chain and it will therefore be readily 65 understood that my improvement can be used in connection with any of the well known forms of sockets now in use.

When it is desired to attach my device to the socket it is only necessary to unscrew 70 the ring and separate the sections sufficiently to take the socket therebetween and the ring is then tightened up securely fastening the socket within the holder and preventing any possible dislocation of the same. The glass- 75 ware can be attached either before or after connecting to the socket.

The ease and rapidity with which this device can be attached to sockets already wired and connected to fixtures renders this im- 80 provement highly important and efficient.

It will thus be seen that I provide a novel construction of holder capable of carrying out all of the objects hereinbefore referred to.

What I claim is:

1. A separable shell forming a socket holder, arms extending from sections of the holder, and shade holding means attached to the opposite ends of said arms. 90

2. A separable shell forming a socket holder, arms extending from sections of the holder, shade holding means attached to the opposite ends of said arms and a ring for clamping the sections of shell holder together. 95

3. A longitudinally divided holder adapted to receive a socket shell therebetween, a clamping ring adapted to fit about said holder and clamp the sections together, arms extending from said sections, and shade holding means attached to the opposite ends of said arms. 100

4. A socket or shell holder formed of longitudinally separable sections, a ring for 105 clamping said parts together, arms extending from said separable sections, an inner disk connected to said arms, and an outer

cup or disk and means for connecting said disks together and holding a shade therebetween.

5. A socket or shell holder formed of longitudinally separable sections, threaded at one end, a threaded ring for binding said sections together, arms connected to said sections, an inner disk connected to the opposite ends of said arms, an outer cup or disk and means for uniting said disk and cup and securing a shade therebetween.

6. A socket or shell holder formed of longitudinally separable sections, a ring for

binding said sections together about a socket, arms connected to said sections, an inner disk connected to the opposite ends of said arms, said inner disk having a centrally extended threaded post, an outer cup through which the threaded post extends and a nut secured upon the extended thread end and binding the inner and outer disks together as set forth.

LAURITZ W. ANDERSEN.
